CLAIM

The ornamental design for an apparatus for measuring light scattering of a sample, as shown and described.

DESCRIPTION

FIG. 1 is a front top perspective view of a first embodiment of an apparatus for measuring light scattering of a sample showing the new design; and,

FIG. 2 is a partial top perspective view thereof.

The broken lines in the figures are shown for the purpose of illustrating portions of the apparatus that form no part of the claimed design.

1 Claim, 2 Drawing Sheets

FIG. 1

FIG. 2
